UNITED STATES PATENT OFFICE.

ALFRED HEALD, OF PHILADELPHIA, PENNSYLVANIA, ASSIGNOR TO MC-
CALLUM, CREASE & SLOAN, OF SAME PLACE.

DESIGN FOR CARPETS.

Specification forming part of Design No. 6,249, dated November 19, 1872.

To all whom it may concern:

Be it known that I, ALFRED HEALD, of Philadelphia, Pennsylvania, have invented a Design for a Carpet-Pattern, of which the following is a specification:

The main features of my design (which is fully represented in and by the accompanying drawing) are the central figure A and the surrounding figures B and C, the latter approximating in general outline to the shape of squares or diamonds and joining each other at the corners. The oblong figure A has a scroll-like border, *a*, a central ornament, *b*, and ornaments *d d*, at its opposite ends, all of a character too clearly shown in the drawing to need description. Each figure B is composed of two sets of radiating arms, *f* and *g*, of the same general character, except that the arms *f*, which

extend to the corners of the figure, are the longest, and the whole of the said arms have the interior foliated ornamentation shown. The figures C have each an ornamented ribbon-like border, *g*, a central ornament, *h*, and ornaments *i* extending beneath the border and joining the opposite ends of the oblong figure A.

I claim—

The design for a carpet-pattern, substantially as described, and as illustrated in and by the accompanying drawing.

In testimony whereof I have signed my name to this specification in the presence of two subscribing witnesses.
